DAVID DICK AND OLIVER W. PRESTON, JR., OF CORNING, NEW YORK.

Letters Patent No. 74,320, dated February 11, 1868; antedated February 8, 1868.

IMPROVEMENT IN PLASTER AND SEED-SOWER.

The Schedule referred to in these Letters Patent and making part of the same.

TO ALL WHOM IT MAY CONCERN:

Be it known that we, DAVID DICK and O. W. PRESTON, Jr., of Corning, in the State of New York, have invented certain new and useful Improvements in Plaster and Seed-Sowers; and we do hereby declare that the following is a full, clear, and exact description of the same, reference being had to the accompanying drawings, and to the letters of reference marked thereon, as forming a part of this specification, in which—

Figure 1 is a side elevation,

Figure 2 a rear view, and

Figure 3 a view of the levers for throwing the machine in and out of gear.

To enable others skilled in the art to make and use our invention, we will now describe its construction and operation.

A represents the plaster and seed-box, which we make V-shaped on the inner side. b is a sliding bar running longitudinally through box A. Said box is provided with pins e e, the object of which will be fully shown hereafter. This bar is also provided with stirrers i i, for the purpose of agitating the grain and fertilizing-material, thereby causing an uninterrupted flow of both. B are the driving-wheels on shaft or axle C. The inner side or circumference of these wheels is cam-shaped, as seen in fig. C, and they being fixed to the axle and revolving with it, a reciprocating motion is imparted to the sliding bar b by the cams working against the pins e e. The rear side of box A is provided with apertures at its bottom to admit of the exit of the grain, &c. D represents a slide, at the centre of which is the small rack g. d is a shaft, upon which is the pinion a. This pinion works in rack g, and by means of which the slide D is opened or closed. h is a lever securely attached to shaft d. k represents a gutter or trough, into which the grain and fertilizing-material fall as they come from box A. m is a revolving shaft, which is provided with a double row of brushes put on or through said shaft in spiral form, as indicated in fig. 2. The object of these brushes is to sweep and scatter the grain, &c., as it falls into the gutter k. n represents a pinion on the end of shaft m. G is a gear-wheel on axle C. By means of this wheel motion is communicated to shaft m in a manner hereinafter shown. o represents a short lever, one end of which is provided with a sleeve, in which the end of shaft m revolves. s is also a lever, slotted as shown in figs. 1 and 3. This lever is securely fastened at the end of shaft d. x represents a connecting-piece, the lower end of which is pivoted to lever o, while the upper end is provided with a slot-pin, which works in the slot in lever s. This pin has a thumb-screw attached to it for securing the connecting-piece x in the slot. y is a pinion on lever o. Thus it will be observed that the operator has entire and complete control over the machine by means of the hand-lever h. p p are slotted pieces provided with ears. Through these ears the shaft d extends and derives its bearings from them. Behind these slotted pieces are the slides c c. These slides rest against the seed-slide D, and are governed by the thumb-screws j j.

The operation of our machine is so obvious that it requires no description to enable one with ordinary intelligence to work it.

What we claim, and desire to secure by Letters Patent, is—

1. The shaking-bar b, when provided with pins e e and stirrers i i, in combination with cam-wheels B B, as and for the purpose set forth.
2. The slide D, provided with rack g, in combination with shaft d and pinion a, substantially in the manner and for the purpose specified.
3. We claim the peculiar gear-arrangement, in combination with shaft m, provided with brushes, shaft d, pinion a, and slide D, substantially in the manner and for the purposes described.

In testimony that we claim the above, we sign our names in presence of two witnesses.

DAVID DICK,
OLIVER W. PRESTON, Jr.
